UNITED STATES PATENT OFFICE.

JAMES F. McCALMONT, OF WAYNE, NEBRASKA.

WATER-ELEVATOR.

SPECIFICATION forming part of Letters Patent No. 291,759, dated January 8, 1884.

Application filed January 19, 1883. (No model.)

To all whom it may concern:

Be it known that I, JAMES F. McCALMONT, a citizen of the United States, residing at Wayne, in the county of Wayne and State of 5 Nebraska, have invented certain new and useful Improvements in Water-Elevators; and I do declare the following to be a full, clear, and exact description of the invention, such as will enable others skilled in the art to which it app- 10 pertains to make and use the same, reference being had to the accompanying drawings, and to the letters and figures of reference marked thereon, which form a part of this specification.

15 This invention pertains to improvements in well-bucket-operating mechanism; and it consists in the combination and arrangement of parts, substantially as hereinafter more fully set forth and claimed.

20 In the accompanying drawings, Figures 1 and 2 represent a front view, partly in section, and a side view, respectively, of my improvement with the bucket just emerging from the well, or partly above the curb. Fig. 3 is a sec- 25 tional elevation, and Figs. 4, 5, and 6 are detailed views thereof with the bucket and its tilting mechanism in different positions.

30 In carrying out my invention I employ up- right side pieces, A A, arranged at opposite sides of the well-curb, and preferably dupli- cated to enable the duplicating of the tilting mechanism, in order that the bucket may be operated from either side.

35 B is the bucket, having two opposite pro- jections or studs, B', at its sides, and sus- pended by a rope, a, or other suitable medium passed through an eye or over a pulley de- pending from the upper cross-piece or top of the side pieces, and from whence it may be 40 passed to a windlass or winding-drum.

45 C are two curved guides secured to the under side of the well-curb, one being adapted to extend in a curvature at one side of the plane of the movement of the bucket and the other to extend in a curvature at the other side of the plane of its movement, and arranged diagonally opposite to the other guide, the purpose of which is to bring the bail of the bucket in alignment with the windlass by the 50 studs B' striking said guides and being brought

into position to enter the slots or grooves in the uprights A.

D D are the tilting or cam levers or devices, pivoted one in each of the opposite side pieces or uprights, A, and adapted to have move- 55 ment within recesses b therein. Also, made in these side pieces or uprights are additional recesses or slots, c c, of an approximate inverted-V shape, and arranged in a plane in front of the levers or tilting device D. It will 60 be noticed that as the filled bucket passes up to near the tilting or emptying point its studs B' will pass in close proximity with the tilting-levers, as seen in Fig. 4, and as the bucket continues its passage the said studs will strike 65 the horns of the levers in the plane of their movement, and thus tilt the levers and throw their lower ends outward against the adjacent uprights A, as seen in Fig. 5, in which position they will be held until the studs of the 70 bucket have passed downward over the upper or cam ends of the levers and into the side recess, b. To permit this latter movement of the studs of the bucket, the hoisting-rope is 75 slackened, the gravity of the bucket which has thus been slightly tilted causing its studs to move down the inclined surfaces or faces of the cam-levers. When the studs of the bucket have escaped from the levers, permitting the latter to assume their original posi- 80 tion, the studs will pass into the beaks or one of the arms of the inverted-V-shaped recesses c, as seen in Fig. 6, when the tilting of the bucket will be completed by continuing to 85 unwind the hoisting-rope, and thus be emp- tied. By slightly pulling upon the hoisting-rope, the bucket will be sufficiently elevated to lift its studs out of said portions of the recesses c and against the under edges of the pawls D, after which, upon continuing to 90 slacken the hoisting-rope, the bucket will de- 95 scend, its studs passing down the longer arms of the recesses c, and thence down inclines of the recesses b, whence they will escape from the levers and the uprights, allowing the buck- et to continue its descent to and into the well and be again filled.

I claim and desire to secure by Letters Patent—

1. In a well-bucket operating or tilting mech-

100

anism, the combination, with the bucket having studs or projections at its sides, of the cam-levers set in recesses in suitable supports, and adapted to guide the bucket to one side of its line of elevation when the hoisting-rope is slackened.

2. In a well-bucket-tilting device, the combination, with the bucket having opposite studs or projections at its sides, of the tilting

cam-levers and uprights having recesses, substantially as and for the purpose set forth.

In testimony whereof I affix my signature in presence of two witnesses.

JAMES F. McCALMONT.
